UNITED STATES PATENT OFFICE.

EARL E. McGREW, OF LINCOLN, NEBRASKA.

FOLDING TABLE.

Application filed September 23, 1921. Serial No. 502,705.

To all whom it may concern:

Be it known that I, EARL E. McGREW, a citizen of the United States, and a resident of Lincoln, in the county of Lancaster 5 and State of Nebraska, have invented certain new and useful Improvements in Folding Tables, of which the following is a specification.

This invention relates to folding tables especially adapted for use by automobile tourists and campers.

An important object is to provide a folding table which is constructed entirely from metal so that the same will not warp or 15 crack as the result of being subjected to dampness or to the strains incident to transporting the same in its folded position.

Further, the invention aims to provide a folding table having a flat metallic top 20 which affords a convenient supporting surface when writing or playing cards and which will support small dishes containing liquids without the possibility of the dishes upsetting.

25 Further, the invention provides a folding table which may be quickly set up or folded and which is provided with no detachable parts which are likely to become lost.

A further object is to provide a folding 30 table which occupies but a small amount of space when folded, and which is durable in use and cheap to manufacture.

Other objects and advantages of the invention will be apparent during the course 35 of the following description.

In the accompanying drawings:

Figure 1 is a perspective of the table.

Figure 2 is a perspective of the same folded.

40 Figure 3 is a plan view of the same partly folded.

Figure 4 is a vertical transverse sectional view through the table set up.

Figure 5 is a perspective of a holding link 45 embodied in the invention.

In the drawing the top of the table is composed of an intermediate section 40 and outer sections 41 and 42, the outer sections being hinged to the intermediate section as 50 indicated at 43 so that the sections may be folded together as illustrated in Figure 2.

The sections 40, 41 and 42 are provided with downwardly directed flanges which strengthen the table top and give the same 55 a neat appearance. The downwardly extending flanges 44 of the intermediate sec-

tion 40 form a supporting means for a pair of cross rods 45 one of which is arranged at each end of the intermediate sections. With reference to Figures 1 and 3, it will 60 be observed that the cross rods 45 are spaced a slight distance from the ends of the intermediate section and slidably support a sleeve 46 to which legs 47 are pivotally connected as indicated at 48. When it is desired to fold the table the legs 47 which are pivotally connected as indicated at 50 may be swung into the position illustrated in Figure 7 so that the same may be swung 65 into contact with the under side of the intermediate section 40. When thus positioned the legs 47 are arranged in substantially parallel relation and occupy but a small amount of space so that the sections 41 and 42 may be swung upon the legs to conceal 70 the same. The legs may be detachably connected by means of a pair of holding rods 51 permanently pivoted at one end to one of the legs of each pair and detachably connected to the outer leg of each pair by means of a pin and slot connection. Of course at any 75 time desired the rods may be swung in parallel relation to the legs 47 to which the same are permanently pivoted.

In carrying out the invention, the legs 47 80 may be braced by means of links 53 permanently pivoted to the legs 47 as indicated at 54 and having their upper end portions extended angularly as indicated at 55 and passed through apertures in the downwardly 85 extending flanges 44. When the links 53 are thus connected with the outer sections 41 and 42 the sections are effectively braced and the legs are also braced to some extent. However when it is desired to close the table 90 it is merely necessary to move the upper portions of the links 53 outwardly so that the attaching members 55 will be disengaged from the flanges 44. The links 53 will now be swung into parallel relation to 95 the links 47 to which the same are attached.

Bracing links 56 are slidably extended through sleeves 57 pivotally connected to the side flanges 44 of the intermediate section as indicated at 58. When in the position 100 illustrated in Figure 5 the links 56 have their angularly extended lower end portions 59 extended through fastening devices 60 carried by the lower portions of the legs 47. The angularly extended end portions 105 59 are, however, detachably extended through the fastening devices 60 so that at 110

any time desired the bracing links 56 may disengage from the fastening devices. There is sufficient friction between the angularly extended end portions 59 and the 5 fastening devices 60 to securely hold the lower portions of the links in engagement with the legs.

When it is desired to fold the table as illustrated in Figure 1 it is merely necessary to disconnect the lower portions of the bracing links 56 and swing the sleeves 57 on the pivot members 58 whereby the links 56 are swung into contact with the bottom or under side of the intermediate 15 section in the manner illustrated in Figure 3. This permits the remaining portion of the table to be completely folded so as to occupy but a small amount of space when being transported.

20 When it is desired to open the table for use the outer sections 41 and 42 are swung into the position illustrated in Figure 7 and the legs 47 are subsequently swung on the pivot point 50 so that the sleeves 46 are moved to the ends of the cross rod 45. The holding rods 51 are now engaged with the legs to hold the same in their extended position and the links 53 may now be connected to the outer sections 41 and 42. 25 Finally the bracing links 56 are swung downwardly and engaged with the fastening devices 60 of the legs 47. By reason of the construction described a table constructed in accordance with this invention 30 is extremely light in weight. The table may be readily swung open or collapsed without

employing tools or without the expenditure of much effort.

Having thus described the invention, what is claimed is:—

40 1. A folding table comprising a top inclusive of a plurality of hingedly connected sections having their edges formed with continuous flanges, cross rods connected to one of said flanges, sleeves slidably and rotatably mounted on said cross rods, legs pivotally connected to said sleeves and capable of swinging to inoperative position with relation to said top, and fastening devices carried by the lower portions of said 50 legs and bracing links having laterally directed terminal portions detachably connected to said fastening devices.

45 2. The construction set forth in claim 1, and a second set of sleeves pivotally connected to one of said flanges and slidably receiving said bracing links.

55 3. The construction set forth in claim 1 and bracing rods pivoted to said legs and having angularly directed terminal portions 60 secured to the flanges and certain of said sections.

65 4. The construction set forth in claim 1 and bracing rods pivoted to said legs and having angularly directed terminal portions secured to the flanges and bracing rods permanently pivoted to certain of said legs and having their terminal portions formed with means for engaging certain of the other legs.

EARL E. McGREW.
